(57) **CLAIM**

The ornamental design for a integrated tool holder for securing a tool, as shown and described.

DESCRIPTION

FIG. 1 is a front perspective view of a integrated tool holder for securing a tool embodying the inventive design;

FIG. 2 is a rear perspective view of an embodiment of the claimed design;

FIG. 3 is a side perspective view of an embodiment of the claimed design in association with a scrench tool shown in broken lines;

FIG. 4 is a second side perspective view of an embodiment of the claimed design in association with a scrench tool shown in broken lines;

FIG. 5 is a top perspective view of one embodiment of the claimed design in association with a chainsaw and a scrench tool shown in broken lines;

FIG. 6 is a side perspective view of an embodiment of the claimed design in association with a chainsaw and a scrench tool shown in broken lines;

FIG. 7 is a bottom perspective view of one embodiment of the claimed design in association with a chainsaw and a scrench tool shown in broken lines; and,

FIG. 8 is a second side perspective view of an embodiment of the claimed design in association with a chainsaw and a scrench tool shown in broken lines.

The broken line showing of structural features and direction lines is included for the purpose of illustrating non-claimed subject matter and forms no part of the claimed design.
